The ornamental design for a protective liner for a ball cap, as shown and described.

DESCRIPTION

FIG. 1 is a first perspective view of a protective liner for a ball cap in accordance with our design;

FIG. 2 is a second perspective view thereof;

FIG. 3 is right side elevation view of the protective liner for a ball cap; the unshown left side elevation view being a mirror image thereof;

FIG. 4 is a bottom plan view of the protective liner for a ball cap;

FIG. 5 is a top plan view thereof;

FIG. 6 is a front elevation view thereof; and,

FIG. 7 is a rear elevation view thereof.

The broken lines in the drawings show the environment in which the design is used. The broken lines form no part of the claimed design.
